APPARATUS FOR DETERMINING THE
LUBRICATING VALUES OF OILSFrederick Ray, Short Hills, N. J., assignor to The
Automatic Appliance Company, St. Louis, Mo.,
a corporation of Missouri

Application July 5, 1929, Serial No. 376,041

3 Claims. (Cl. 265—11)

This invention is directed to a novel apparatus for determining the lubricating values of oils as they are used, for example, in automotive engines and the like.

As is well known, the bearings and cylinders of automotive engines are lubricated by a combined pressure and splash system which circulates the lubricant round and round for use over and over again until it loses its lubricating value. The most commonly employed lubricant is mineral oil, which is readily miscible with the lighter hydro-carbon fuels, such as gasoline and kerosene. These lighter fuels are not always completely consumed in the operation of the engines, but instead, some of the fuel collects on the relatively cold cylinder walls and subsequently finds its way past the pistons into the crank case, where it becomes mixed with the lubricating oil. As a result, the lubricant gradually becomes diluted, with a consequent reduction in viscosity for lubricating value.

Of course, the absolute effect of dilution upon viscosity is dependent upon the original viscosity, percentage of dilution, and operating temperatures, and varies widely under different conditions. In some instances, for example, such as occur in ordinary practice, a dilution of from 10% to 20% will reduce the viscosity of the mixture to about one third of the viscosity of the pure oil. The various lubricating oils used in automotive engines differ widely in viscosity at any given temperature, and the viscosities of all the different oils vary widely with the temperature. These oils are subjected to mean temperatures, in the crank case, of from below 0° F. in winter to 150° F. or more in summer, and such variations in operating temperatures, with resultant variations in the vaporization and condensation of the fuel, produce substantial variations in the rate of dilution. Furthermore, the setting of the carburetor, the improper use of the choke, and the mechanical condition of the engine—particularly the fit of the piston rings in the cylinders—as well as the manner of use of the engine, each contribute in varying degrees to the diluting tendency.

In order to maintain the viscosity of the lubricant above a certain critical value, it has been customary to use an oil having a greater viscosity than is actually necessary, and then to drain the crank case and replenish with fresh oil at the end of every five hundred or one thousand miles of travel. But from a consideration of the above-mentioned variable factors that affect the viscosity of the oil, it is evident that the rate of

dilution of the oil is not a function of the distance travelled or of the number of hours of operation.

The seriousness of this problem has long been recognized, but no satisfactory solution has been presented prior to this invention. Some automobile manufacturers have installed in their cars various devices for heating the lubricating oil to drive off, by distillation, the more volatile gasoline or kerosene as soon as it is mixed with the oil. Such devices, aside from being complicated and cumbersome, are disadvantageous in that the additional heating of the oil tends to break it down by increasing the rate of carbonization. Furthermore, there is no way for the operator to know whether the device is functioning or not, and in the event that it should cease to function over a distance of two thousand miles, serious damage might result to the engine. Other manufacturers have provided their engine crank cases with ventilating means to carry off any vapors of the diluting gasoline or kerosene, but devices of this sort are far from being efficient, and the operator is left totally in the dark.

The foregoing and other objectionable features of the prior art are overcome by the present invention, which has for its object the provision of a novel apparatus for determining and indicating at all times variations in the lubricating properties of the oil in an automotive engine or motor while in operation.

In its broader aspects, the invention contemplates the determination of the lubricating properties of the oil by the translation of some other property or condition into terms of viscosity.

More specifically, the method involved consists in passing a relatively small amount of the oil through a circulating system and creating therein a pressure which is a function of the viscosity of the oil. Variations in said pressure are measured by a suitable gauge or the like which may be calibrated to give an exact indication of the viscosity. The circulating system is preferably auxiliary to the regular lubricating system of the motor (being in the nature of a by-pass in circuit therewith) and is provided at one point with a pressure regulator which maintains a constant pressure on the oil at that point in the system and receives the oil from the usual pump thereof. From this point of constant pressure, the oil is caused to flow successively through a small bore capillary tube and a capillary orifice, one leading to and the other from a common pressure chamber. Since the oil in flowing through the tube and the orifice is obedient to different laws of flow, there will be created in the common cham-

ber a pressure which is a function of the viscosity of the oil. It is this pressure which is utilized in operating the indicator, and consequently any change of pressure due to a change of viscosity will be immediately registered by the indicator. In this way, the operator is advised at all times as to the viscosity of the oil and will know exactly when it has lost its lubricating value and needs replenishing. So long as the indicator shows the oil to possess the requisite viscosity under proper operating conditions, it may be safely used as a lubricant without regard to actual mileage or period of use of the engine.

The foregoing and other objects, features, and advantages of the invention will more readily appear from the following description in connection with the accompanying drawings, wherein the invention has been shown by way of illustration, and wherein:

20 Fig. 1 is a perspective view, partly broken away, showing one form of the invention as applied to an automobile;

25 Fig. 2 is a vertical longitudinal sectional view through one form of the improved viscometer, and showing the indicating gauge associated therewith;

28 Fig. 3 is a side elevation of the viscometer; and Fig. 4 is a top plan view thereof, partly broken away.

30 In Fig. 1, one form of apparatus has been shown as applied to an automobile, but it is to be understood that the invention is not restricted to such use, but may be employed with equal advantage in other automotive engines, such as 35 for aviation and marine use, and in fact in lubricating systems of machines other than gas engines.

38 The apparatus comprises a viscometer 1 connected in a closed circulating system at one side 40 of the engine 2, said system including an oil pump 3 of any ordinary or preferred type. The pump 3 draws oil from a sump at the bottom of the engine crank case through a suction pipe 4, and forces said oil through a supply pipe 5 leading to the engine bearings. The pump 3 and pipes 4 and 5 are parts of the usual pressure lubricating system employed in automobiles, and this system is so well known as to require no further description.

45 The viscometer 1 is connected to the supply pipe 5 by mean of a branch of a T 6, so that a small portion of the oil from the pump 3 is bypassed through the viscometer 1 and subsequently returned to the oil sump through discharge pipe 7. The oil passing through the viscometer 1 is caused to flow in such manner as to create a pressure which varies (inversely) with the viscosity of the oil, and variations in such pressure are adapted to be registered by an indicator or 55 gauge 8 on the dashboard of the vehicle, said gauge being connected with the viscometer by means of a pipe or tube 9.

60 Referring particularly to Figs. 2, 3, and 4, it will be seen that the viscometer unit 1 comprises a relatively shallow circular body portion 10 and a relatively long and narrow cylindrical extension 11 at one side thereof. These two portions may be formed integrally as a single casting, or they may be formed separately of castings, or of sheet metal, and secured together in any suitable manner. The body portion 10 is provided with a shallow cavity or recess 12 which constitutes an oil receiving chamber within which a constant pressure is maintained on the oil by a pressure regulator 13.

65 This pressure regulator comprises a flexible corrugated diaphragm 14, which forms the upper wall of the pressure chamber 12, having a central reinforcement 15 against which the lower end of a compression spring 16 bears. The spring 16 is confined within a chamber 17 of a housing 18, which is secured, as by screw threads 19, to the body portion 10. The diaphragm 14 may preferably be soldered to an annular shoulder 20 on the body portion 10, or it may be clamped in position between said body portion and the housing 18. The upper end of the spring 16 bears against the shouldered inner end 21 of an adjustable screw plug 22 in the upper end of the housing 18, and by turning said screw plug the pressure of the spring against the diaphragm may be varied as desired. The screw plug 22 is formed with a central bore 23 for a purpose to be explained hereinafter, and is locked in adjusted position by a screw cap 24.

26 In the center of the bottom wall of the chamber 12, there is a flared opening 26 through which oil is adapted to flow into said chamber from a longitudinal bore 27 or passage in a downwardly extending boss 28 of the body portion 10. Disposed within the bore 27, below the opening 26, is an oil strainer 29 of any desired construction, this strainer being clamped in the end of the bore 27 by means of a bushing 30, which in turn is held in place by a coupling nut 31. The bushing 30 is secured to a nipple 32 which branches out from the T 6 before alluded to.

33 The flow of oil through the opening 26 is controlled by a valve 35 which is associated with the pressure regulator 13. This valve 35 is in the nature of a flat disc having a ball joint connection at 36 adjacent the lower end of a valve stem 37 extending through the opening 26 and threaded through the reinforcing member 15. The ball joint connection at 36 allows the valve to rock slightly about the axis of the ball, so that the flat upper surface of the valve disc may seat tightly against the annular valve seat 38 surrounding the lower end of the opening 26. Normally, the pressure of the spring 16, in acting upon the diaphragm 14, maintains the valve 35 in its open position, but if the pressure of the oil within the chamber 12 should rise beyond a predetermined amount, the diaphragm will yield upwardly, drawing the valve stem 37 with it and causing the valve disc to approach the valve seat 38 and reduce the flow of the oil through the opening 26, thereby maintaining a given constant pressure within the chamber 12.

40 In order to adjust the valve with reference to the valve seat, and thereby to vary the extent of its movement, the lower end of the valve stem 37 is provided with a head portion having a screw-driver slot 39. Thus, when the body portion of the viscometer is disconnected from the circulating system, a screw-driver may be inserted in the bore 27 to turn the stem 37 in the reinforcing member 15. The stem is so proportioned that its threaded end extends beyond the upper side of the reinforcing member 15 for the reception of a lock nut 40, which may be loosened or tightened as desired by means of a socket wrench inserted through the bore 23 of the plug 22.

45 To provide an outlet for the oil from the chamber 12, a coiled small bore or capillary tube 43 is embedded in the body portion 10, as best shown in Figs. 2 and 4. This tube 43 has its inlet end 44 extending upwardly into the chamber 12 and its outlet end 45 extending into a longitudinal bore or chamber 46 formed in the cylindrical ex-

tension 11. Between its two ends, the tube 43 is curved around in such manner as substantially to encircle the boss 28 in the base of the body portion 10, thus giving a proper length to the tube while maintaining it within a small compass. The tube 43 is so proportioned as to permit streamline flow of the oil therethrough, for a purpose which will be explained presently.

Screwed or otherwise secured in the lower end 10 of the cylindrical portion 11, and in communication with the bore or chamber 46 therein, is a nozzle member 47 having at its lower end an annular wall 48 formed with a capillary orifice 49 which preferably is slightly larger than the mesh of the strainer 29 and which causes a turbulent flow. The wall 48 is tapered or flared both above and below the orifice to produce a sharp edge orifice, which is a type of orifice best suited for the present instrument. The orifice 49 discharges into the upper end of the return pipe 7, which may be secured to the lower end of the cylindrical portion 11 by any ordinary or preferred form of coupling or union 50. A vent tube 51, which is open at its upper end, is connected with the pipe 7 to maintain atmospheric pressure below the orifice 49, altho a small vent cut through the pipe 7 would answer the purpose equally well.

In the prior art liquids have been passed through relatively large orifices to determine their viscosity, the use of such orifices in all instances being based upon the fact that the pressure drop causing the flow was substantially independent of the viscosity and consequently varies as the square of the velocity through the orifice. To obey this law of flow with liquids of relatively high viscosity such as lubricating oils used in automobiles the size of the orifice and pressure drop must be such that a large amount of oil passes through the orifice, in fact many times that available in the lubricating system of an automobile.

I have discovered that when such liquids flow through a small orifice the flow is not independent of viscosity and consequently the pressure drop causing the flow does not vary as the square of the velocity. In the case of such an orifice the law of flow (which I believe to be an entirely new discovery) is that the pressure multiplied by a factor (which is a function of viscosity but a constant for a given viscosity) is equal to the velocity to the n th power, n being a continuous function of the viscosity. I have found that n varies continuously from about 2 in the case of water or liquids of substantially zero viscosity to about 1 in the case of liquids of high viscosity.

As is well known, the pressure drop to cause the flow of the liquid through a small bore or capillary tube is directly proportional to the velocity of the liquid. Likewise the pressure drop 60 to cause flow is directly proportional to the viscosity. When n has a value of 2 the flow is substantially free from the effect of viscosity, the pressure head being entirely transformed into velocity head. When n has a value of 1 the flow 65 is entirely viscous, the pressure head being utilized entirely in overcoming the shearing resistance to flow. For intermediate values of n part of the pressure head is utilized to overcome shear and part is transformed into velocity head. As 70 a consequence for all values of n greater than 1 the variation in the pressure drop to cause flow will be less than the variation in viscosity.

I have used the term "capillary orifice" in the specifications and claims to designate a small orifice having the above flow characteristics. I

have ascertained that such flow characteristics hold for small orifices of minute or pinhole order of magnitude. How large the capillary orifice may be made and still produce a flow which is dependent on the viscosity is still problematical and I am not now prepared to give any definite size limits for the orifice covering the range over which the law set forth holds true.

From the foregoing, it will be clear that any variation in the viscosity of the oil circulated 10 through the instrument will result in a change of pressure within the chamber 46, and hence by a suitable calibration of the gauge 8, a direct reading in terms of viscosity can be had. Accordingly, one end of the tube 9 is connected by a 15 coupling or union 55 with the upper end of the cylindrical portion 11, the other end of said tube 9 extending to the gauge 8, which is located on the instrument board as previously explained. The gauge 8 may be of ordinary commercial form 20 having pressure-responsive means, such as a Bourdon tube, bellows, or diaphragm, to cause rotation of a pointer 56. The gauge 8 has a graduated dial reading from zero to 2 in a counterclockwise direction, the magnitude of the divisions gradually decreasing as they approach the value 2. The pointer 56 is shown pointing to the zero mark which corresponds to the maximum pressure within the chamber 46, which condition 25 would result from the passage through the viscometer of a fluid having zero viscosity. This is an ideal condition which does not exist in reality, but which is closely approximated with water. Under conditions of atmospheric pressure in the chamber 46, the pointer 56 will be in its extreme 30 position limited by a stop pin 57.

Since the total pressure drop through the instrument from the chamber 12 to the pipe 7 is constant, and since the same quantity of liquid flows through the capillary tube 43 and capillary 40 orifice 49, it follows that the proportional distribution of this drop in the tube and orifice will vary as the viscosity varies. In consequence, the pressure in the chamber 46 relative to the atmosphere will vary, and this variation will be indicated by the gauge 8 connected thereto.

The proportions of the tube 43 and orifice 49 may be varied within reasonable limits and in accordance with requirements of design for particular instruments. By way of illustration, satisfactory results have been obtained with the device shown in the drawings, wherein the orifice 49 is about .035 inch in diameter, and the tube 43 is about $\frac{3}{16}$ inch in inside diameter and about 5 inches in total length. The pressure maintained within the chamber 12 by the regulator 13 may be about three pounds to the square inch, the spring 16 being adjustable merely to suit the calibrations of the gauge 8.

The relative arrangement of the small bore 60 tube 43 and capillary orifice 49 can be reversed if desired but I prefer the first-disclosed arrangement wherein the oil first flows through the tube and then through the orifice. As has previously been stated, with this preferred arrangement the pressure in the chamber 46 will vary 65 inversely with the viscosity, and this is desirable because it prevents any possible damage to the gauge when the viscosity is high due to low temperatures, as when starting the engine in cold 70 weather. In other words, as the viscosity decreases the pressure in the common chamber 46 increases, and the gauge can be so selected and calibrated, as to be capable of withstanding the maximum pressure caused by the flow of the 75

least viscous fluids. If the pressure were to vary directly with the viscosity, it is conceivable that in starting in cold weather, the oil might be so thick as to create a pressure beyond the range 5 of the gauge, causing injury to the instrument which would render it inaccurate and undependable in future use.

It will now be apparent that an apparatus has been provided for continuously testing, determining, and indicating the viscosity of the oil in an automotive engine while it is in operation, so that the operator will be advised at all 10 times as to the actual lubricating value of the oil. When the indication given by the gauge 8 reaches a predetermined minimum value for that particular engine, he will know that the oil requires to be changed irrespective of the distance he might have travelled since the last 15 change. But until such indication is given, he will know that the oil is satisfactory for use and 20 need not be wasted. Thus the instrument is of great utility in that it saves the engine when the oil is bad, and it saves the oil when the oil is good.

25 Obviously the invention is susceptible of numerous modifications in the construction of the apparatus, and the right is herein reserved to make such changes as fall within the scope of the appended claims without departing from the 30 spirit of the invention.

35 The words "indicator" and "indicating" occurring in the appended claims are used in their broadest sense and are intended to cover any form or manner of indication, whether a visual indicator, alarm or signal, recording instrument or otherwise.

Having thus described my invention, what I claim is:

1. A viscometer for determining the viscosity 40 of oil which is subjected to destructive influences affecting its viscosity, comprising an oil receiving chamber, a yieldable diaphragm forming one wall of said chamber, a spring acting on said diaphragm to maintain a constant pressure within said receiving chamber, a pressure-regulating valve associated with the diaphragm to control the flow of oil into the receiving chamber, a variable pressure chamber adapted to be supplied with oil from the receiving chamber and provided with a capillary orifice as an outlet 45 for the oil, means for regulating the outlet pressure at the orifice so that a constant pressure drop is maintained between the oil receiving

chamber and the outlet of the orifice, a small bore capillary tube of substantial length for conducting the oil from the receiving chamber to said variable pressure chamber, said tube and orifice being so proportioned as to cause viscous 5 flow through the tube and partially non-viscous flow through the orifice so as to create within the pressure chamber a pressure which is dependent upon the viscosity of the oil, and means for indicating variations in said pressure in 10 terms of viscosity.

2. A viscometer of the class described, comprising a casing having a shallow oil receiving chamber, a diaphragm forming a yieldable wall for said chamber, a self-aligning valve associated 15 with the diaphragm to control the flow of oil into said receiving chamber, a compression spring acting against the diaphragm to maintain a substantially constant pressure in the receiving chamber, a fine-mesh strainer through which oil 20 is caused to flow before entering said chamber, a variable pressure chamber at one side of the receiving chamber, a nozzle in the bottom of said variable pressure chamber and provided with an outlet orifice slightly larger than the mesh 25 of said strainer, said orifice leading into a conduit having an atmospheric vent, a small bore tube for conducting the oil from the receiving chamber to said variable pressure chamber, said tube intermediate its ends being coiled beneath 30 the receiving chamber, and said tube and orifice being so proportioned as to create within the pressure chamber, a pressure which is a function of the viscosity of the oil, and an indicator responsive to the variations in pressure in the 35 pressure chamber to indicate variations in viscosity.

3. Apparatus for continuously indicating the viscosity of a fluid, which comprises a variable-pressure chamber, a capillary tube providing an 40 inlet to said chamber, a capillary orifice providing an outlet from said chamber, said capillary tube causing stream line flow and the orifice causing turbulent flow of the fluid passing therethrough, means for maintaining substantially constant initial and final pressures on the fluid passing through the apparatus irrespective of any change 45 which may occur in the fluid, and means for measuring pressure in said chamber to give an indication of the viscosity of the fluid at any time.

FREDERICK RAY.
